Atty.

UNITED STATES PATENT OFFICE.

CHARLES W. HUBBARD, OF WESTON, MASSACHUSETTS.

WINDING-MACHINE.

1,394,732.

Specification of Letters Patent. Patented Oct. 25, 1921.

Application filed September 25, 1919. Serial No. 326,177.

To all whom it may concern:

Be it known that I, CHARLES W. HUBBARD, a citizen of the United States, residing at Weston, county of Middlesex, State of Massachusetts, have invented an Improvement in Winding-Machines, of which the following description, in connection with the accompanying drawing, is a specification, like characters on the drawing representing like parts.

In my United States Patent No. 1,258,411, dated March 5, 1918, I have illustrated and described a twisting and winding machine which comprises a yarn container in the form of a can or receptacle, a winding head constructed to build up a yarn mass in said yarn receiver or container in which the yarn is laid in layers or loops extending transversely to the axis of the yarn receiver, and a yarn support in said yarn container on which the yarn mass is built up, said yarn support having a frictional engagement with the walls of the yarn container so that as the yarn mass increases the yarn support will be forced downwardly in the yarn container, the frictional engagement between the yarn support and container affording sufficient resistance to the downward movement of said yarn support so that the yarn will be laid compactly.

In the use of the device illustrated in Figure 1 of said patent it sometimes happens that the yarn support will move downwardly in the yarn container as the yarn mass increases with a jerky or hitching motion, this being due to the fact that the frictional resistance between the yarn support and the yarn container will hold the support from movement, and as the winding proceeds, the increasing amount of yarn between the yarn support and the winding head produces an increased pressure which finally overcomes the frictional resistance of the yarn support against the walls of the container and forces the yarn support downwardly. The frictional resistance between two bodies which are relatively stationary is often greater than that between the same bodies when they are moving relative to each other, and hence as soon as a sufficient pressure has been developed by the increasing yarn mass to overcome the static frictional resistance between the yarn support and the yarn container and said support moves downwardly, the resistance between the moving yarn support and the wall of the container is less than that

when the yarn support was stationary and, therefore, the elasticity of the compressed yarn mass will cause the yarn support to move a considerable distance before it comes to rest. This forward movement of the yarn support will reduce the pressure between the same and the winding head, and as the winding head proceeds to increase the yarn mass, the pressure of the yarn mass against the yarn support will be again increased to a point sufficient to overcome again the static frictional resistance between the yarn support and the container.

The compactness with which the yarn is laid at any time depends upon the pressure between the winding head and the yarn support, and where the yarn support moves downwardly with an intermittent or step-by-step movement, as above described, the yarn mass will be laid more loosely at those points in the yarn mass where the winding head is operating under reduced pressure and will be laid more compactly at those points where the winding head is operating under increased pressure. The result of this operation is that a yarn mass will be produced which is uneven in density.

The object of my present invention is to provide an improved form of yarn support by which the above intermittent or step-by-step movement of the yarn support will be entirely eliminated and which will have an even gradual downward movement at all times, thus producing a yarn mass which has an even density throughout.

In order to give an understanding of my invention, I have illustrated in the drawings a selected embodiment thereof which will now be described, after which the novel features will be pointed out in the appended claims.

In the drawings, Fig. 1 is a view partly in section of a winding apparatus embodying my invention;

Fig. 2 is a section on the line 2—2, Fig. 1;

Fig. 3 is a section on the line 3—3, Fig. 2.

In the drawings, 1 indicates the yarn receiver which is in the form of a cylindrical can or container and 2 indicates generally a rotary winding head adapted to lay or wind a yarn mass 3 in the yarn receiver in layers extending transversely to the axis of rotation. This winding head is provided with a winding plate 4 which rests on the yarn mass 3, and is also provided with a vibrating yarn-guiding finger 5 by which

the yarn is laid, said yarn passing from the finger 5 through a slot in the winding plate 4.

I have not shown herein any details of the 5 winding head as this may have any suitable construction adapted to lay the yarn mass 3 in loops or layers extending transversely to the axis of rotation.

My improved yarn support on which the 10 yarn mass 3 is laid comprises a supporting plate 6 on which the yarn mass 3 rests and a novel frictional device yieldingly connected to the plate and constructed to develop the required frictional resistance against the 15 walls of the container 1. This frictional device comprises a split friction band 8 which has frictional engagement with the walls of the container 1 and is yieldingly held in engagement therewith. This split 20 band 8 is herein shown as comprising a metallic band 9 to which is secured a lining 10 of suitable friction material. The friction material which is commonly used for brake linings of automobiles answers the 25 purpose in a satisfactory manner. The metallic band 9 is provided at its ends with the brackets 11 and 12, the bracket 11 having a spring-positioning projection 13 extending therefrom and the bracket 12 having an 30 adjusting rod 16 screw-threaded therethrough, said rod 16 carrying an adjusting nut 14 which forms the backing for a spring 15, one end of which is held in position by the projection 13 and the other end of which 35 encircles and is held in position by the end of the rod 16. 17 is a check nut carried by the rod or pin 16 to assist in holding it in adjusted position. The spring 15 thus acts as an expanding spring which tends to expand 40 the split ring 8 into frictional contact with the walls of the container 1, and the construction shown provides means for readily adjusting the tension of the spring and thereby adjusting the frictional engagement 45 between the band and the container 1. This split band 8 is carried by a supporting plate 7 which is yieldingly secured to the plate 6. The metallic ring 9 is provided with inwardly-directed slotted projections 18 which 50 overlie the plate 7, and the plate 7 is provided with guiding projections 19 which extend through the slots 18 and serve to guide the split band in its expanding or contracting movements. These projections 19 are in 55 the form of screws or bolts which extend through the plate 7 and the slots in the projections 18, said bolts being provided with nuts 20. For yieldingly connecting the frictional member to the yarn-supporting plate 6, said plate is shown as provided with a 60 depending boss or hub 21 and the plate 7 is shown as provided with an upwardly-directed boss or hub 22 into which is screwed a connecting screw 23 that extends loosely through the hub 21, and the head 24 of which 65

is received in a recess 25 formed in said hub. 26 is a spring which encircles the two hubs and tends to hold the plates 6 and 7 separated as far as the screw 23 will permit. Since said screw 23 is slidably mounted in 70 the hub 21, the two plates can move toward each other from the position shown in Fig. 1. Such movement, however, will be resisted by the spring 26. 27 is a guiding projection depending from the plate 6 and entering a 75 recess 28 formed in a stud 29 rising from the plate 7, this projection serving to hold the two plates from turning relative to each other.

The operation of this device is as follows: 80

Assuming that the device is operating with the parts in the position shown in Fig. 1, any increase in the amount of yarn in the yarn mass 3 will increase the downward pressure against the plate 6 since the plate 85 4 is incapable of vertical movement, and such downward pressure will be resisted by the frictional engagement between the split friction band 8 and the walls of the container 1.

As the pressure increases, the spring 26 90 is compressed slightly until the pressure reaches a point sufficient to overcome said frictional resistance, at which time the plate 7 with the friction band 8 thereon will move downwardly a slight distance, but owing to 95 the presence of the spring 26 which maintains the upward pressure on the plate 6, said plate will not partake of such downward movement of the friction device, but will only move downwardly with a gradual 100 movement due to the gradual increase of the size of the yarn mass. The member on which the yarn mass is supported, therefore, will have a uniform downward movement as the yarn mass is built up, notwithstanding 105 any variation in downward movement which the friction device may have. Thus the yarn mass will be subjected at all times to a uniform pressure which will result in producing a uniform tension on the yarn as 110 it is drawn in and therefore a yarn mass of uniform density.

I claim:

1. In a device of the class described, the combination with a yarn container, of means 115 to wind a yarn mass therein in transverse layers, and a yarn support for the yarn mass, said yarn support comprising a plate on which the yarn rests, a friction member having frictional engagement with the yarn 120 container, and a yielding connection between said plate and friction member.

2. In a device of the class described, the combination with a yarn container, of means to wind therein a yarn mass which is laid 125 in transverse layers, a friction member having frictional engagement with the walls of the yarn container, and a plate on which the yarn rests and which is yieldingly supported by said friction member.

3. In a device of the class described, the combination with a yarn container, of means to wind the yarn mass therein, and a yarn support within said container and on which the yarn mass is built up, said support having a split friction band yieldingly held in engagement with the walls of the container.

4. In a device of the class described, the combination with a yarn container, of means to wind the yarn mass therein, a friction member within the container, said friction member comprising a split friction band yieldingly held against the walls of the container, and a plate yieldingly sustained by

said friction member and on which the yarn mass rests.

5. In a device of the class described, the combination with a yarn container, of means to wind the yarn mass therein, a friction member within the container, said friction member comprising a split friction band yieldingly held against the walls of the container, a plate on which the yarn mass is supported, and a spring interposed between said plate and friction member.

In testimony whereof I have signed my name to this specification.

CHARLES W. HUBBARD.
